US00D592822S

(12) **United States Design Patent**
Boucher et al.

(10) **Patent No.:** **US D592,822 S**
(45) **Date of Patent:** **** May 19, 2009**

(54) **DEVICE FOR HOLDING AND POSITIONING CONSTRUCTION MATERIALS**

(75) Inventors: **Lawrence Boucher**, St-Philibert (CA);
Romeo Arvinte, St-Laurent (CA)

(73) Assignee: **A. Richard Tools Co.**, Quebec (CA)

(**) Term: **14 Years**

(21) Appl. No.: **29/304,798**

(22) Filed: **Mar. 7, 2008**

(51) LOC (9) Cl. **12-05**

(52) U.S. Cl. **D34/31**

(58) Field of Classification Search **D34/31, D34/28; 254/93 H, 131, 120, 8 R; 52/344, 52/347, 352, 470, 459; 414/11, 800**

CLAIM

We claim, the ornamental design for a device for holding and positioning construction materials, as shown and described.

DESCRIPTION

FIG. 1 is a perspective view of a device for holding and positioning construction materials showing our new design;

FIG. 2 is a front elevational view thereof;

FIG. 3 is a top plan elevational view thereof;

FIG. 4 is a bottom plan view thereof;

FIG. 5 is a right side view thereof;

FIG. 6 is a rear elevational view thereof; and,

FIG. 7 is a left side view thereof
